CLAIM

The ornamental design for a headwear with tails, as shown and described.

DESCRIPTION

FIG. 1 is a top plan view of headwear with tails showing my new design;

FIG. 2 is a bottom plan view thereof;

FIG. 3 is a front elevational view thereof;

FIG. 4 is a rear elevational view thereof;

FIG. 5 is a side elevational view thereof, the opposite side is a mirror image;

FIG. 6 is a side elevational view of a second embodiment the only difference being the length of the tails; and,

FIG. 7 is a perspective view with the tails in a tied position.

FIG 1

FIG 2

FIG 3

FIG 4

FIG 6
